[57] **CLAIM**

The ornamental design for a juice cart, as shown and described.

DESCRIPTION

FIG. 1 is a front and right side perspective view of a juice cart showing my new design;

FIG. 2 is a right side elevational view thereof, the left side elevational view being a mirror image of that shown;

FIG. 3 is a front elevational view thereof;

FIG. 4 is a rear elevational view thereof;

FIG. 5 is a bottom plan view thereof; and

FIG. 6 is a top plan view thereof.

*fig. 3.**fig. 4.*

*fig. 5.**fig. 6.*
